UNITED STATES PATENT OFFICE

2,669,198

FLOOR SAFE

Rex H. Campbell, Oakland, Calif., assignor, by direct and mesne assignments, of one-half to Walter P. Ross and one-half to Robert Q. Bramlet, both of Oakland, Calif.

Application December 26, 1947, Serial No. 793,773

5 Claims. (Cl. 109—59)

1

The invention relates to a safe or vault unit.

An object is to provide a safe of the character described having a locking means which will maintain the safe in locked condition even though the exposed and externally accessible bolt control elements are rendered inoperative or are removed.

A further object is to provide generally improved locking devices for safes of the character described.

Another object of the invention is to provide safe units of the character described which are particularly arranged for flush installation in floors, or walls, and particularly those of business establishments, for the safe-keeping of money and other valuables.

The invention possesses other objects and features of advantage, some of which, with the foregoing, will be set forth or be apparent in the following descriptions of typical embodiments thereof, and in the accompanying drawings, in which:

Figure 1 is a perspective and broken-away showing of the receptacle portion of a safe embodying my invention.

Figure 2 is a top perspective view of a removable door for the safe.

Figure 3 is a perspective view of a flush cover plate for the receptacle of Figure 1.

Figure 4 is an underneath face view of the door of Figure 2.

Figure 5 is an edge and partly sectional view of the closure door.

Figure 6 is a partly sectional view of the door taken at the broken line 6—6 in Figure 5.

Figure 7 is a plan section of the installed door, the view being taken at the plane of the line 7—7 in Figure 5.

Figure 8 is an upright axial and broken-out sectional view of the complete safe assembly, 40 with the door shown in full side elevation.

Figure 9 is a fragmentary sectional view taken at the line 9—9 in Figure 7.

Figure 10 is a fragmentary and perspective view of the container portion of another embodiment of the safe.

Figure 11 is a perspective view of a key-locked door for use with the container of Figure 10.

Figure 12 is an inner side view of the safe door of Figure 11.

Figure 13 is an upright axial sectional view of the present safe having its door mounted on its container portion.

Figure 14 is a plan section taken at the plane of the line 14—14 in Figure 13.

2

Figure 15 is a section of the door taken at the line 15—15 in Figure 12.

The embodiment of my invention disclosed in Figures 1 to 9 inclusive comprises a straight-sided cylindrical receptacle or container 17 arranged for permanent installation in a floor or wall, a door 18 for locked mounting at the access opening of the storage portion of the receptacle, and a cover plate 19 removably engaging the top of the receptacle 17 above the lockable door 18 and provided with a finger hole 20 centrally thereof for facilitating its removal and placement. The receptacle 17 comprises a cylindrical side wall 21 which extends from a base plate 22 to which it is integrally attached, as by welding. The base plate 22 is preferably of polygonal outline to provide portions projecting beyond the wall 21 for use in anchoring the container in its installed position; Figure 8 discloses the container as embodied in a retaining body 23 of concrete, the top face 23' of said enclosing concrete body being flush with the top face of the mounted cover plate 19.

At a distance from its top which permits the supported installation of the cover 18 thereon below the mounted cover plate 19, a jamb portion of the receptacle wall 21 provides a flat annular door-supporting seat 24 defining the access opening for the storage space. In the present structure, the seat 24 comprises an intermediate and outwardly facing annular step provided in the container wall 21, said wall being thicker beyond said seat. The present door 18 comprises a generally cylindrical one-piece body member 25 which carries the locking mechanism and has a radial flange extension 26 at its outer side for the flat engagement of its inner side with the seat 24 whereby the door is rotatable while engaging the seat and the remaining portion of the supported body 25 is arranged to extend inwardly of the plane of the seat 24. At its inner side, the door body 25 provides a radial flange 27, said flange being generally cooperative with the outer door flange 26 to define an annular groove 28 concentric with the body axis and of uniform width axially of the body.

Lugs 31 and 32 and 33 extend inwardly from the container wall 21 below the seat 24, said lugs being spaced generally equally about the circle of the wall 21. In the present structure the lugs 31 and 32 and 33 comprise legs of generally L-shaped elements having their other legs fixed to the wall 21, as by welding, and the thickness of the lugs axially of the container is slightly less than the axial width of the groove 28 whereby

the lugs may extend freely into said groove. Radial notches 34 and 35 and 36 extend inwardly from the periphery of the flange 27 in such an arrangement that the lugs 32 and 33 may simultaneously register with the notches 35 and 36 when the lug 31 registers with the notch 34, said notches dividing the flange into arcuate lug portions 37 and 38 and 39 extending beyond the cylinder of the door body. Circumferentially of the container, the lugs 31 and 32 and 33 are narrower than the respective notches whereby the cover 18 may be moved to or from its seat when, and only when, the lugs and notches are mutually registered in the indicated manner. As particularly shown, the lugs 31 and 32 are rectangular, the lug 33 is generally triangular, the notches 34 and 35 are arcuate with radial ends, and the lug 36 is triangular and generally complementary to the notch 36.

When the door 18 has the outer portion of its flange 26 engaged with the seat 24, it may be positioned to dispose the set of notches in registration with the corresponding lugs to permit a raising of the cover from its seat and from the container, or be positioned to dispose the notches between the lugs whereby the latter may cooperate with the door lugs 37 and 38 and 39 to prevent a removal of the cover from its mounted position in the container. In the present arrangement, the inner faces of the receptacle lugs 31 and 32 and 33 are coplanar in a plane perpendicular to the container axis, and the outer faces of the door lugs 37 and 38 and 39 are coplanar in a plane perpendicular to the door axis; the arrangement is such that said planes are parallel in close opposition when the door is seated in the receptacle.

Preferably, and as shown, only a predetermined and limited rotation of the door 18 is permitted between its released and retained positions; in the present structure stop elements 40 and 41 are fixed between the door flanges 26 and 27 in positions for their engagement by opposite sides of the door ear 31 to limit the degree of rotation of the mounted door 18 between the position in which the door is removable and the position in which the door is locked in its operative position.

It will now be noted that the triangular lug 33 has one free edge 33' generally radial to the door circle while its other free edge 33'' makes an acute angle with the edge 33' and may be cooperative with the outer end of a bolt 42 which is extendable into the groove 28 for variable distances in accordance with the disposal of the lug 33 with respect thereto. As particularly shown, the bolt 42 is of uniform cross-section and is slidable in a complementary bore 43 which is provided in the door body 25 and extends radially of the body in the plane of the groove 28. The inner end of the bore 29 is closed and receives a compression spring 44 between its closed end and the inner end of the bolt 42 for constantly and yieldingly urging the latter to a limiting extended position in the groove 28. The notch 36 of the bottom flange 27 of the cover has a radial side 36' and an oblique side 36'', and the line of the bolt 42 is substantially at the point of intersection of the notch side 36'' with the circle of the flange 27.

The present latching arrangement is essentially such that a clockwise rotation of the cover 18 from its position of installation upon the seat 24 will engage the outer bolt end with the sloping lug edge 33'' as a wedging or camming

face to progressively force back the bolt until the lug side 33' is reached and the bolt is freed for its spring-pressed extension behind the lug to prevent a return, and releasing, rotation of the cover. As the bolt 42 engages behind the lug edge 33', the stop 40 reaches the lug 31 for preventing a further rotation of the door, while a return movement of the unlocked door is limited by the engagement of the stop 41 with the lug 31 to provide for the positioning of the door for its removal.

Noting that the bolt 42 is operative as a latch bolt with respect to the lug 33, means are provided for withdrawing the bolt against the resistance of the spring 44 when the installed door is to be rotated to the position thereof which permits its removal as a closure for the container space, such a bolt-withdrawing means being under control solely of a person authorized to open the safe. As particularly shown, the bolt 42 is provided with a longitudinal and diametrical slot 42' near its inner end, and an upwardly extending pin 45 engages the slot for effecting an inoperative disposal of the bolt when desired. The pin 45 extends upwardly from an actuator member 46 mounted at the inner side of the door and through a slot 47 extending in the cover body 25 from its inner end to the bore 43 and in parallel relation to the bolt line. The actuator 46 has a limited movement toward the door edge from its pin-withdrawing position whereby it is cooperative with the inner end of the bolt slot 42' to limit the projection of the bolt 42 under the influence of the spring 44.

It will now be noted that the actuator member 46 extends from the mechanism of a combination lock 48, said lock including a casing 49 fixed to the inner door side and enclosing the lock mechanism and being rendered operative to displace the actuator 46 from its normal extended position by the actuation of a knob 51 extending from the outer door face and mounting a circular dial 52 for the appropriate reference of its number (or letter) indicia 53 to a reference mark 54 provided on the door. The connecting mechanism between the knob 51 and the actuator 46 is such that a pre-determined sequence of settings of certain dial indicia 53 with respect to the reference point 54 is arranged to connect the actuator 46 with the knob for its displacement to effect a withdrawal of the latch bolt 42 upon an appropriate rotative movement of the knob 51. The connecting mechanism between the knob 51 and the actuator 46 may be that of any standard combination lock, is not itself a feature of present invention, and is therefore not further shown. It is to be particularly noted that the pin 45 extends axially of the door whereby a removal of the casing 49 which carries the lock mechanism at and beyond the inner door side will disengage the pin from the bolt slot 42', and so make impossible a withdrawing of the bolt unless the actuator 46 is appropriately operated in its appointed position.

As shown, the combination lock 48 is disposed to one side of the center of the door 18, and a handle 55 extends from the outer door face diametrically thereof for use in manipulating the door with respect to the seat 24. The present cover plate 19 has its peripheral edge stepped from beneath to provide for its centered mounting on the top edge of the receptacle wall 21 while the door 18 is operatively mounted on the seat 24. Preferably, and as shown, the cover plate 19 is of laminated structure having an outer

lamination 19' of metal and an inner lamination 19'' of suitable heat insulation material adherent to the first lamination; in the present instance, the plane of joining of the laminations 19' and 19'' is that of the edge step of the plate. The central finger hole 20 of the cover plate extends through both laminations of the plate, and the outer face of the plate may be flush with the outer face 23' of the concrete mass in which the container is embedded, as shown in Figure 8.

In the embodiment of Figures 10 to 15 inclusive, the safe receptacle 57 is arranged for closing by a door 58 which is installable at the receptacle lip by reason of the fact that the lock release is provided by a key-controlled mechanism which extends entirely inwardly of the outer cover face which may therefore be disposed in flush relation with a floor or wall surface from which the safe extends, no cover plate then being needed. In the present structure, the tubular receptacle wall 61 extends integrally from an end plate 62, and has its bore stepped outwardly near its top to provide a circular seat 64 for engagement by the outer door flange 66 which extends integrally from the door body 65 having a radial flange 67 extending integrally from the inner body end to define a groove 68 between the flanges, the door jamb thus being at the receiving end of the receptacle.

Lugs 71 and 72 and 73 extend inwardly from the receptacle bore portion which is at the inner side of the seat 64 and defines the access opening for the storage space of the safe, said lugs corresponding respectively in form and function to the lugs 31 and 32 and 33 of the previously described embodiment of my invention; the lug 73 provides a bolt-camming edge 73'' and a bolt-catching edge 73'. Notches 74 and 75 and 76 in the inner cover flange 67 define lugs 77 and 78 and 79 between them, said sets of notches and lugs corresponding in form and function to the sets of notches and lugs provided in the flange 27 of the door 18 of the first-described embodiment. Stop pins 80 and 81 mounted in and between the outer flange 66 and the radial flange 67 of the cover limit the permitted rotation of the door 58 engaging the seat 64 to and from its installation position.

It will be noted that the lugs 77 and 78 and 79 of the door 58 are respectively cooperative with the lugs 72 and 73 and 71 for retaining the door in closing position in the access opening until the free door is rotated to align the notches 74 and 75 and 76 with the lugs 71 and 72 and 73 respectively. It will therefore be understood that the present cooperative relation of the receptacle and door lugs is the same as that provided in the previously described embodiment of my invention.

A cylindrical latch bolt 82 extends in and from a radial socket bore 83 provided in the door body 65 between the flanges 66 and 67 of the door, and is urged to maintain a limiting outward position in the bore 83 by the action of a compression spring 84 engaged between the inner socket end and the opposed end of the bolt. Near its inner end, the bolt 82 is provided with a longitudinal slot extending diametrically through it, and said slot receives a control pin 85 which extends from an actuator arm 86 extending radially from the inner end of a key-controlled tumbler barrel 91 which extends axially through the door body in swivelled relation thereto, said pin being freely swingable through a slot 87 provided in the door body inwardly of and opposite the bolt-carry-

ing bore 83. The outer end of the tumbler barrel 91 preferably extends no further than the flat outer face of the door, and is normally held against its rotative displacement for a withdrawing of the bolt 82 by elements (not shown) which are arranged to be rendered inoperative only by and upon the insertion of a suitable key 91' in a complementary key-receiving slot 91'' extending axially into the tumbler barrel from its outer end.

Means are preferably provided for added protection against an unauthorized release of the door for its removal from the access opening of the present safe, said means being normally operative to prevent the actuation of the key-released tumbler barrel 91 for a withdrawal of the bolt 82, and generally comprising a key-controlled stop member which normally engages the pin 85 against its bolt-withdrawing actuation.

As particularly shown, a tumbler barrel 92 extends axially through the door body 65 in appropriately spaced relation to the tumbler barrel 91, and fixedly carries a disc member 93 at its inner end and having its plane between the inner door end and the plane of operation of the arm 86 whereby the peripheral edge 93' of the disc is normally engageable by the bolt-withdrawing pin 85 when the arm 86 is freed for its operative actuation. The disc 93 is provided with a slot 93'' extending radially inwardly from its periphery and disposable to permit a bolt-withdrawing movement of the pin 85 therein. The tumbler barrel 92 preferably extends no further than the outer face of the door, and is arranged for its freeing only by and upon the insertion of an appropriate key 92' in a complementary key-receiving slot 92'' extending into the tumbler barrel from its outer end.

For releasing the locked present door 58 for its removal from the access opening, the appropriate key 92' must first be inserted in the tumbler barrel 92 and used for turning the freed tumbler barrel to align the disc slot 93'' with the slightly arcuate path of displacement of the pin 85, and the subsequent rocking of the arm 86 by means of an inserted key 91' which has freed the tumbler barrel 91 for its turning is operative to release the door for its rotation by means of a handle 95 to the position from which it may be axially removed from the receptacle 57. As shown, the handle 95 comprises a U-shaped element having its side portion 95' slidable in axial holes through the door body and provided with stop elements 96 at the free ends, the cross portion 95'' of the handle normally seating in a suitable depression 97 connecting said holes at the outer door face.

It will be understood that the present requirement for the use of two cooperative keys to release the actuator arm 86 for its bolt-withdrawing displacement provides an improved locking control for rotary safe doors generally. It will also be noted that the present arrangement precludes a withdrawal of the latch bolt 82 should either or both of the key-controlled tumbler barrels 91 and 92 be rendered inoperative or be removed as by driving them inwardly. Also, the present key-controlled release of the latched door for its removal in the described manner avoids the need for a separate cover plate for the receptacle by reason of the fact that the tumbler barrels 91 and 92 do not extend beyond the outer face of the door.

From the foregoing description taken in connection with the accompanying drawings, the ad-

vantages of the present floor safe features will be readily understood by those skilled in the art to which the invention appertains. While I have described the principles of operation, together with arrangements which I now consider to comprise preferred embodiments thereof, I desire to have it understood that the showings are primarily illustrative, and that such changes and developments may be made, when desired, as fall within the scope of the following claims.

I claim:

1. In a safe or vault, a body providing a receptacle having an access opening defined by a circular jamb portion providing an outwardly facing door seat interiorly of the receptacle, fixed retaining lugs extending into the opening from its side and inwardly of the seat, a rotary door for disposal against said seat and having retaining lugs extending from it and arranged for simultaneous door-retaining disposal inwardly of corresponding first lugs in close adjacency thereto, a spring-pressed latch bolt reciprocably carried by the door structure and normally cooperative between the door and a said jamb lug for locking the retained door against a freeing rotation thereof with respect to the jamb lugs, a bolt-withdrawing actuator reciprocably mounted on the door and being disposed on the innermost side of the bolt, and a mechanism normally operative from the outer door side for operatively actuating said actuator solely by an authorized person, inward displacement of the actuator being operative to disengage it from the bolt whereby the bolt will remain in locking engagement with the receptacle.

2. A structure in accordance with claim 1 whereof the actuating mechanism comprises a key-controlled member requiring the application thereto of a particular key to render it operative for withdrawing the latch bolt.

3. A structure in accordance with claim 1 whereof the actuating mechanism comprises a key-controlled member requiring the application thereto of a particular key to render it operative for withdrawing the latch bolt, a displaceable stop member normally disposed to block a withdrawal of the latch bolt by the operative key-controlled member, and means under control of an authorized person to dispose the stop member out of the latch bolt blocking position.

4. A structure in accordance with claim 1

whereof the said mechanism comprises a rotary member requiring a particular combination setting thereof to render it operative for effecting a withdrawal of the latch bolt.

5. In a safe or vault, a body providing a receptacle having an access opening defined by a circular jamb portion providing an outwardly facing door seat intermediately of the receptacle, fixed retaining lugs extending into the receptacle opening from its side and inwardly of the seat, a rotary door comprising a disc-shaped body for disposal against said seat and having retaining lugs extending fixedly from it and arranged for rotation into simultaneous door-retaining disposal inwardly of corresponding first named lugs in close adjacency thereto, a spring-pressed latch bolt reciprocably and directly carried by and in the door body and normally cooperative between the door and a said jamb lug for locking the retained door against a freeing rotation thereof with respect to the jamb lugs, a bolt-displacing actuator mounted on the door for rectilinear displacement in a line parallel to the line of action of the bolt and having a portion thereof positioned inwardly of the bolt, an actuator-control assembly carrying the actuator and including a rotary member swivelled in the door for rotation about a fixed axis transverse to the door and arranged for actuation from the outer door side and connected with the actuator for operatively displacing the same on manipulation by an authorized person, and a pin member carried by the actuator and normally engaging the bolt for a withdrawal of the bolt by and upon a displacement of the actuator effected by a rotation of the rotary member from its normal position, an inward displacement of the actuator being adapted to disengage it from the bolt while the bolt is operative.

REX H. CAMPBELL.
